CLAIM

The ornamental design for a combined butter dish and cover with magnetic holder for butter knife, as shown and described.

DESCRIPTION

FIG. 1 is a front perspective view of a combined butter dish and cover with magnetic holder for butter knife showing my new design;

FIG. 2 is a left view thereof;

FIG. 3 is a top view thereof;

FIG. 4 is a bottom view thereof; and,

FIG. 5 is an exploded top perspective view thereof.

The broken lines are for illustrative purposes only and form no part of the claimed design.
